UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

PRESSED-STEEL TRUCK.

SPECIFICATION forming part of Letters Patent No. 408,031, dated July 30, 1889.

Application filed May 23, 1889. Serial No. 311,876. (No model.)

To all whom it may concern:

Be it known that I, EDWARD WILLIAM MACKENZIE HUGHES, of Chicago, Cook county, Illinois, have invented a new and useful Improvement 5 in Trucks, of which the following is a full, true, and exact description, reference being had to the accompanying drawings.

This invention relates to an improvement in pressed-steel trucks, by which I am enabled to 10 provide a swinging bolster in a truck unprovided with end pieces and in which the rigidity of the truck is insured by the transom.

My invention will be readily understood from the accompanying drawings, in which—

15 Figure 1 represents an elevation; Fig. 2, a plan; Fig. 3, a vertical central section; Fig. 4, a longitudinal section through the wheel-frame, showing the method of supporting the transom; and Fig. 5, a horizontal section 20 through the transom and wheel-frame.

The wheel-frames are shown at A connected by the double transom B B.

C represents the bolster.

25 The wheel-frames A are made of pressed steel; and the essential part of the present improvement consists in the pockets D D, pressed in the wheel-frames in the process of manufacture.

30 The bolster-beams B B are box-shaped, having ends E, integral therewith, fitting the pockets D D. The transom B B is provided with suitable bearings for the swing-hangers G G,

Fig. 4, which are formed into stirrups in the well-known way. The bolster is by preference of pressed steel provided with bearing- 35 surfaces for the swing-hangers; but this structure forms no part of my present application.

The box-shaped transoms B, having closed ends, are attached, and by preference riveted, 40 as shown, in the pockets D D, and the transoms B are therefore supported in these pockets independent of the riveting, the shape of the pocket and the end of the transom insuring metallic support without riveting. 45

What I claim as my invention, and desire to secure by Letters Patent, is—

1. The combination, in a car-truck, of the wheel-frames A, having a pocket D, with the pressed-steel box-transom B, the end thereof 50 fitting the pocket D, substantially as described.

2. The combination of the wheel-pieces A A, having pockets D D D D, with the pressed-steel box-transom B B, having the ends of the 55 boxes B B riveted in the pockets D D D D, substantially as described.

In testimony whereof I have signed my name to this specification in the presence of two subscribing witnesses.

EDWARD WILLIAM MACKENZIE HUGHES.
